UNITED STATES PATENT OFFICE.

WILLIAM S. PRITCHARD, OF DETROIT, MICHIGAN, ASSIGNOR TO MOTOR PRODUCTS CORPORATION, OF DETROIT, MICHIGAN, A CORPORATION OF NEW YORK.

METHOD OF SECURING METALLIC STRIPS.

Application filed September 10, 1920. Serial No. 409,453.

To all whom it may concern:

Be it known that I, WILLIAM S. PRITCHARD, a citizen of the United States of America, residing at Detroit, in the county 5 of Wayne and State of Michigan, have invented certain new and useful Improvements in Methods of Securing Metallic Strips, of which the following is a specification, reference being had therein to the 10 accompanying drawings.

The invention relates to the method of securing metallic strips and has for its object the forming of a strip of uniform thickness and pliability comprising a plurality 15 of metallic strips of short lengths secured end to end. Other objects of the invention reside in further features as more fully hereinafter set forth.

In the drawings:

- 20 Figure 1 is a top plan view of a machine for carrying out my method;
Figure 2 is a side elevation thereof;
Figure 3 is an end elevation of the clamping mechanism;
25 Figure 4 is a cross section on the line 4—4 of Figure 3.

Figure 5 is a sectional elevation through the reel.

1 is the table of the machine for carrying 30 out the method of securing metallic strips end to end and is mounted upon the standards 2. 3 is a laterally extending support upon one of the forward standards 2 and provided at its outer end with the transversely extending cylindrical rod 4 upon which the coils 5 of the metallic ribbon are sleeved. 6 is a U-shaped guide pivotally mounted upon the support 3 and adapted to embrace the coil 5, the ribbon of which 35 is being operated upon. This guide normally rests upon the rod 4. 7 is a weighted arm having the bar 8 at its outer end to which the weight 9 is secured and to the inner end of which the parallel spaced bars 10 are secured, the inner ends of the latter being pivotally mounted upon the support 3 and connected thereto by the same pivot that connects the inner end of the guide 6 to the support. 11 is a roll pivotally mounted 45 between the parallel spaced arms 10 near their upper ends and adapted to rest upon the coil 5, the metallic strip leaving this coil passing beneath.

12 and 13 are pairs of cooperating rolls

mounted upon the supports 14 and 15 respectively on the table 1 near its forward end, these rolls being adapted to tension as well as guide the metallic strip in passing to the clamping mechanism which comprises the spaced clamps 16 and 17 mounted upon 50 the base 19 upon the table 1. These clamps have side flanges 18 for guiding the strip and each of the upper clamping members 20 of these clamps is adapted to be vertically raised and lowered by means of a hand lever 65 21 which is pivotally mounted upon an arm 22 secured to its respective lower clamping member and having the eccentric slot 23 therein which engages the pin 24 at the upper end of the upper clamping member. 70

In securing the metallic strips of the coils 5 to each other, one strip is passed through the guide and tension rolls 12 and 13 and the clamps 16 and 17 until its rear end has passed through the forward clamp 16, when the clamp 17 is actuated to tightly grip this strip. The succeeding strip is then passed through the guide and tension rolls and through the forward clamp 16 with its forward end adjacent the rearward clamp 17 80 so that the adjacent end portions of the two metallic strips overlap each other. The forward clamp 16 is then operated by its hand lever 21 to firmly grip the last-mentioned strip. 85

The next operation consists in cutting the overlapping end portions of the strip and preferably at an angle to the longitudinal axes of these strips. This is accomplished by means of the shears 25, the upper shearing member of which is operated by means of the hand lever 26. These shears when not in operation are removed from the path of travel of the metallic strips and occupy the position shown by the dotted lines 27 in Figure 1. To move the same into operative position as shown by the full lines in this figure, they are longitudinally slid into place and extend at the desired angle to the longitudinal axes of the strips. 95

After the adjacent ends of the strips have been cut at an angle to their longitudinal axes, the ends of the strips are drawn apart to produce a gap therebetween sufficient to compensate for the expansion of the metal and for the solder which secures the same to each other. This gap is preferably predetermined and as shown is produced by 100 105

means of moving the forward clamp 16 toward the front of the machine. In detail, the forward clamp 16 is slidably mounted upon the base 19 and is adapted to be moved by means of the lever 16' secured to the eccentric shaft 16² upon which is mounted an eccentric bushing engaging the forward clamp base. A suitable flux such as borax is then applied to the adjacent ends 10 of the strips and they are heated to approximately 1200° Fahrenheit by suitable means such as the torch 28, which is universally mounted upon the table 1 and is adapted to occupy the position between the clamps 16 and 17 as shown by the dotted circular line 29. Hard solder is then applied to the adjacent ends of the strips to secure the same to each other.

For the purpose of flattening the joint 20 between these strips, there is a clamp 30 which is movable transversely of the metallic strips and between the clamps 16 and 17. This clamp, as shown in Figures 3 and 4, comprises the upper and lower jaws 31 and 32, respectively, which are pivotally mounted at their rear ends upon the plate 33 longitudinally slidably mounted in the support 34 and actuated by the lever 35 pivoted at its lower end to the support 34 25 and having the elongated aperture 36 through which extends the pin 37 which is secured to the plate 33 and extends between the body portions of the jaws 31 and 32. For moving the upper and lower jaws 31 and 32 toward each other in order to clamp the opposite sides of the joint between the strips when the jaws are moved inwardly, they are provided with the slots 38 having the parallel portions 39 and the diverging portions 40. These slots are engaged in by pins 41 fixedly secured to the support 34. Thus, after the brazing operation, the joint is 45 tightly gripped to flatten the same by means of swinging the handle lever 35 toward the front side of the machine when the jaws will occupy the position shown by the dotted line 42 in Figure 1.

After the flattening operation has taken place, the strips pass toward the rear end of the machine through the pair of cooperating guide rolls 43 and the joint is annealed to make the same pliable to run through the machine without breaking when being bent. This joint, in annealing, is first heated to a 55 temperature of approximately 900° Fahrenheit by the torch 28, which is adjustable to occupy the position as shown by the circular dotted line 44 in Figure 1, after which the joint is dipped in water contained in the tank 45 upon the table 1. After removing the joint from the tank 45, the lower and upper faces of the joint are held in contact with the polishing wheel 46 driven from the motor 47, which polishing wheel finishes the 60 faces of the joint and makes the same con-

tinuous with the corresponding faces of the adjacent ends of the strips.

The strip then passes through the spaced pairs of cooperating guide rolls 48 and 49 intermediate which is located the tank 50 70 transversely slidably mounted upon the base 51 secured to the table 1. For cleaning the joint it is dipped into one of the compartments of the tank containing suitable cleaning acid such as muriatic acid and then 75 dipped into the other compartment of the tank 50 containing water to remove the muriatic acid, the tank 50 being transversely adjusted intermediate these last two steps. After passing through the pair of cooperating guide rolls 49, the strip is passed between the cooperating buffing wheels 52, both of which are vertically adjustable by means of right and left hand screws, in order to maintain a permanent relation with the center line of travel of the copper ribbon. These buffing wheels are suitably driven from the motor 53, which is mounted upon the table 1. From the buffing wheels, the metallic strip passes through the pairs of 80 cooperating tension rolls 53 and to the reel 54 upon which it is coiled, the tension rolls being provided to produce a uniform tension upon the strip while being coiled.

As shown in Figure 2, the jointed portion 95 of the strip occupies the positions shown by the full lines, and after the different operations have been performed and during the time the jointed strip is being reeled at the rear end of the machine, the strip occupies 100 the positions shown by the dotted lines between the pairs of guide and tension, rolls 13 and 49.

The reel, as shown, comprises the annular flanges 55 which are spaced from each other 105 and mounted upon the hub 56 in turn rotatably mounted upon the spindle 57 secured to and extending transversely of the upper end of the standard 58. This standard is carried upon the truck 59, which is provided with positioning uprights 60 having slotted upper ends through which extend the positioning rods 61 pivotally mounted upon the rear standards 2. For rotating the reel 54 there is a friction drive wheel 62 which is 110 adapted to engage the periphery of one of the flanges 55 and is driven by means of the motor-driven wheel 63 engaging its periphery. 64 is a brake adapted to engage 115 the periphery of the driving flange 55, this brake being normally held in engagement with the periphery by means of the compression coil spring 65 between adjacent ends of the rod 66 pivotally secured to the brake and the rod 67 pivotally secured to one of the rear standards 2, there being a sleeve 68 surrounding adjacent ends of these rods and also the coil spring.

69 is a foot lever connected to the brake 64 by means of the rod 70 for releasing the 130

brake from engagement with the reel. In order that the portion of the metallic strip between the tension rolls and the reel be constantly under tension, the brake 64 forms the support for the friction drive wheel 62 and the axis of its pivot registers with the axis of the shaft for the motor-driven wheel 63, the arrangement being such that the release of the brake engages the friction drive wheel 62 with the driving flange of the reel and on the other hand the release of the friction drive wheel re-engages the brake.

From the above description it will be readily seen that I have devised a simple method for forming a metallic strip comprising a series of metallic strips of shorter lengths. Furthermore, the method produces a strip which has a continuous flat surface side and is pliable throughout its length. Another very important consideration is that the method is such that it may be carried out in a machine of comparatively short length.

What I claim as my invention is:

25. 1. The method of securing metallic strips, comprising the successive steps of clamping the strips with overlapping ends, simultaneously cutting the overlapping ends, separating the ends, heating and brazing the same, and clamping the joint while cooling.
2. The method of securing metallic strips, comprising the successive steps of clamping the strips with overlapping ends, simultaneously cutting the overlapping ends at an angle to their longitudinal axes, separating the ends, applying a flux thereto and heating and brazing the same, clamping the joint while cooling, and subsequently annealing the joint.
30. 3. The method of securing metallic strips which comprises the overlapping thereof, the simultaneously cutting of the overlap-

ping portions, and the integrating of the adjacent ends.

4. The method of securing metallic strips 45 which comprises the overlapping thereof, the simultaneously cutting of the overlapping portions, the integrating of the adjacent ends, and the annealing of the joint.

5. In the method of securing metallic 50 strips the steps of positioning ends of successive separate strips adjacent to each other, the integrating of the adjacent ends and the annealing of the joint.

6. The method of securing metallic strips, 55 comprising the clamping thereof with overlapping ends, the cutting of the overlapping ends, the separating of the ends and then the soldering of the ends.

7. The method of securing metallic strips, 60 comprising the successive steps of clamping the strips with overlapping ends, simultaneously cutting the overlapping ends, separating the ends, brazing the ends and annealing and cleaning the joint.

8. The method of securing metallic strips, 65 comprising the successive steps of clamping the strips in alignment with each other and with overlapping ends, simultaneously cutting the overlapping ends, separating the 70 ends, heating and brazing the ends, annealing the joint, polishing the sides of the joint, washing the joint with acid, and subsequently washing the joint with water.

9. The method of securing metallic strips, 75 comprising the clamping of the strips with overlapping ends, the successive steps of cutting the overlapping ends, separating the ends, soldering the ends, annealing the joint, cleaning the joint, and reeling the secured 80 strips under substantially constant tension.

In testimony whereof I affix my signature.

WILLIAM S. PRITCHARD.
